DESIGN FOR A PHOTOGRAPHIC CAMERA

Clinton H. Harris, Ann Arbor, Mich., assignor to International Industries, Inc., Ann Arbor,
Mich., a corporation of Michigan

Application June 29, 1940, Serial No. 93,324

Term of patent 7 years

To all whom it may concern:

Be it known that I, Clinton H. Harris, a citizen of the United States, residing in the city of Ann Arbor, in the county of Washtenaw and State of Michigan, have invented a new, original, and ornamental Design for Photographic Camera, of which the following is a specification, reference being had to the accompanying drawing, forming a part thereof.

I claim:

The ornamental design for a photographic camera, substantially as shown.

CLINTON H. HARRIS.
